UNITED STATES PATENT OFFICE.

HARRY WARD LEONARD, OF EAST ORANGE, NEW JERSEY.

ELECTRICALLY-HEATED TOOL.

SPECIFICATION forming part of Letters Patent No. 678,410, dated July 16, 1901.

Application filed April 24, 1898. Serial No. 538,878. (No model.)

To all whom it may concern:

Be it known that I, HARRY WARD LEONARD, a citizen of the United States, residing in the borough of Manhattan, city and county of 5 New York, State of New York, (formerly residing at East Orange, in the county of Essex and State of New Jersey,) have invented a certain new and useful Improvement in Electrically-Heated Tools, of which the following 10 is a specification.

My invention relates to apparatus in which electric energy is converted into heat—such as rheostats, electrically-heated tools, and electric heaters—and more particularly relates 15 to apparatus intended to be operated at comparatively high temperatures—such, for instance, as flat-irons; and it consists in so disposing the heating-conductor that it is free to expand and contract without injurious mechanical strain and so that it is in contact 20 only with a medium which does not cause any chemical depreciation of the heating-conductor, said conductor being so arranged that a very long length may be placed in a comparatively small space.

Furthermore, my invention consists in distributing the heating-conductor within the flat-iron, so that the heat energy developed in the heated conductor will be uniformly dissipated and the maximum amount conducted to the working surface.

In carrying my invention into effect I employ an infusible insulating material, such as steatite, in solid form as a core or support for 35 the heating-conductor. This material is given the desired shape by working it on a lathe or otherwise, the preferred form being cylindrical. When the material is shaped into the desired form, I cut a very fine screw-thread upon its surface, into which a very fine heating-conductor is wound. The number of threads to the inch and the size of the 40 conductor will vary according to the heat energy required.

50 A screw-thread on a cylindrical core provides a simple and rapid way of applying the heating-conductor to its support, and when a very fine conductor is employed the same can be uniformly wound on the core without any difficulty whatever, which is a matter of considerable importance. I have found it extremely desirable to give the thread upon

the core a solid clean smooth surface, and particularly the side walls thereof, because the heating-conductor when placed therein 55 will be free from depreciation by mechanical stress or chemical combination, and the conductor lying in the thread makes a very uniform and perfect contact with the surface, and the conductor itself is uniformly heated. 60 The threads also prevent contact between the turns of the conductor, even though its expansion by heat causes it to rise somewhat from the bottom of the thread, in which case the conductor would adjust itself uniformly so as to make good contact along one 65 of the side walls of the thread between the top and bottom of the thread. This constant uniform contact of the conductor with its support prevents the conductor from becoming overheated at different points, and thus saves the conductor from burning out.

The flat-iron is a solid casting having no joints in the metal which will retard the flux of heat from the heating-conductors to the 70 working surface. This casting is provided with a number of cylindrical holes parallel to the longer axis of the iron, and in these holes I place the cores having the heating-conductors wound thereon. By providing 75 several holes in one casting for the cores carrying the heating-conductors better conduction of heat to the working surface is obtained. These cores may be about three-quarters of an inch in diameter. By employing 80 four cores I may wind them to one standard and use four of them, whether for one hundred and twenty-five, two hundred and fifty, or five hundred volt circuits, by coupling them all in multiple or two in multiple 85 series or all in series, respectively.

My invention is illustrated in the accompanying drawings, in which—

Figure 1 is a plan view of a flat-iron, the cores carrying the heating-coils and the lead-ing-in wires being shown in dotted lines; Fig. 2, an end view of the flat-iron with the end plate carrying the circuit-terminals and binding-posts removed; Fig. 3, a sectional view on the line $\alpha\alpha$ of Fig. 1; and Fig. 4, an enlarged view of a portion of one of the cores, with the heating-conductor and wrapping of insulation shown in section.

Referring to the drawings, A is the flat-

iron, having four cylindrical holes, into which are inserted the cores B, of insulating material, having the heating-conductor C wound thereon. A layer D of insulation is placed 5 between each core and the surrounding metal. This may be done by covering the cores after the conductors are wound thereon with any suitable material. A simple and effective way of doing this is to apply a wrapper of 10 mica, or the cylindrical holes may be lined with insulation. The rear end of the iron has a recess a, which is covered by a plate A', of insulating material, carrying binding-posts a² and a³ for the circuit-wires. The object of 15 the recess a is to leave ample room for the leading-in wires e, which connect the heating-coils with the circuit-terminals, and to guard against contact with the surrounding metal. These wires may be led directly to the bases 20 of the binding-posts, but to avoid crossing of the wires and to facilitate the making of connections I employ two metal terminals e² and e³, secured to the inner side of plate A' and connected, respectively, with the binding-posts 25 a² and a³. The heating-coils, as shown in Fig. 1, are connected in multiple.

The leading-in wires e must be insulated, since they are liable to become short-circuited; but in practice these conductors 30 become quite hot, and it is very important to insulate them with a material which will withstand a high heat and not interfere with the flexibility of the conductors. I have found that disks, blocks, or beads e' of solid refractory or infusible insulating material, with the 35 wires threaded through them, give good results, because the disks or beads do not impair the flexibility of the wires and they are easily applied to the wires at the desired place.

40 What I claim is—

1. In an apparatus wherein electric energy is converted into heat, the combination of a cast-iron body or support, and several separable resistances carried thereby and arranged 45 so that they lie in close proximity to the cast-iron body or support practically throughout their length, whereby a large portion of the heat energy developed in said resistances under operative conditions will be 50 rapidly transmitted to said cast-iron body or support.

2. In an apparatus wherein electric energy is converted into heat, the combination of a cast-iron body or support, and several separable resistances mounted on separate supports carried by said cast-iron body or support and arranged so that the resistances lie 55 in close proximity to the cast-iron body or support practically throughout their length, whereby a large portion of the heat energy developed in said resistances under operative conditions will be rapidly transmitted to said cast-iron body or support.

60 3. In an apparatus wherein electric energy is converted into heat, the combination of a cast-iron body or support provided with a se-

ries of cylindrical holes, and a series of separate conductors wound upon cylindrical cores adapted to be inserted into the cylindrical holes, whereby the conductors will lie 70 in close proximity to the cast-iron body or support practically throughout their length, and whereby a large portion of the heat energy developed in said conductors under operative conditions will be rapidly transmitted 75 to said cast-iron body or support.

4. In an apparatus wherein electric energy is converted into heat, the combination of a cast-iron body or support provided with a series of cylindrical holes, and a series of separate conductors wound upon cylindrical cores made of steatite adapted to be inserted 80 into the cylindrical holes, whereby the conductors will lie in close proximity to the cast-iron body or support practically throughout 85 their length, and whereby a large portion of the heat energy developed in said conductors under operative conditions will be rapidly transmitted to said cast-iron body or support.

5. In an apparatus wherein electric energy 90 is converted into heat, the combination of a cast-iron body or support provided with a series of cylindrical holes, a series of separate conductors wound upon cylindrical cores adapted to be inserted into the cylindrical 95 holes, whereby the conductors will lie in close proximity to the cast-iron body or support practically throughout their length, and whereby a large portion of the heat energy developed in said conductors under operative 100 conditions will be rapidly transmitted to said cast-iron body or support, circuit-terminals carried by the cast-iron body or support, and insulated conductors connecting said terminals with the separate conductors on the 105 cores.

6. A flat-iron having a series of cylindrical holes, and cores having heating-conductors wound thereon and adapted to be inserted in said holes, and whereby the heating-conductors are held in close proximity to the surrounding metal of the flat-iron practically throughout their length, and whereby a large portion of the heat energy developed in said conductors under operative conditions will 115 be rapidly transmitted to the surrounding metal.

7. A flat-iron having a series of cylindrical holes, and cores of insulating material having heating-conductors wound thereon and adapted to be inserted in said holes, and whereby the heating-conductors are held in close proximity to the surrounding metal of the flat-iron practically throughout their length, and whereby a large portion of the 120 heat energy developed in said conductors under operative conditions will be rapidly transmitted to the surrounding metal, and a layer of insulation between the cores carrying the conductors and the surrounding metal of the 125 flat-iron.

8. A flat-iron having a series of cylindrical

holes, cores having heating-conductors wound thereon and adapted to be inserted in said holes, and whereby the heating-conductors are held in close proximity to the surrounding metal of the flat-iron practically throughout their length, and whereby a large portion of the heat energy developed in said conductors under operative conditions will be rapidly transmitted to the surrounding metal, a plate 5 for covering the opening at one end of the iron through which the cores are inserted in the cylindrical holes, circuit-terminals carried by said plate and to which the heating-conductors are connected, and binding-posts 10 on said plate for the external circuit connections, substantially as set forth.

15 9. A flat-iron cast in one piece and having

a series of cylindrical holes formed therein, and cores having heating-conductors wound thereon and adapted to be inserted in said 20 holes, and whereby the heating-conductors are held in close proximity to the surrounding metal of the flat-iron practically throughout their length, and whereby a large portion of the heat energy developed in said conductors under operative conditions will be rapidly 25 transmitted to the surrounding metal.

This specification signed and witnessed this 21st day of April, 1896.

H. WARD LEONARD.
